UNITED STATES PATENT OFFICE.

OSCAR C. RIXSON, OF NEW YORK, N. Y.

DOOR-CLOSING MECHANISM.

1,025,309.

Specification of Letters Patent.

Patented May 7, 1912.

Application filed February 3, 1909. Serial No. 475,885

To all whom it may concern:

Be it known that I, OSCAR C. RIXSON, citizen of the United States, residing at New York, in the county of New York and State 5 of New York, have invented a certain new and useful Improvement in Door-Closing Mechanism, of which the following is a full, clear, concise, and exact description, reference being had to the accompanying drawings, forming a part of this specification.

The invention relates to means for closing a door, and is especially adapted to a double-acting door mounted to be swung open in either direction from the normal closed 15 position.

Among the objects of the invention are to cause the door to be closed positively, yet without banging; to hold the door normally closed, as against wind pressure or the like; 20 to provide adjustments for the door-closing and door-checking devices, so that the same may be independently regulated for varying conditions; to provide such leverage in connection with the mechanism that the door-closing devices (and the door-checking devices) exert their maximum effect while the 25 door is in its closed position, so that the act of opening the door meets with gradually less resistance after the initial movement.

30 In its preferred form the invention comprises means (such as a spring) for closing the door, and in co-operation therewith means (such as liquid checking-mechanism) for retarding the closing-movement with 35 certainty to prevent the slamming and banging of the door.

Furthermore, as applied to double-acting doors, the invention comprises additional closing-means (a second spring) and additional retarding-means (a second checking-mechanism) co-acting together to operate 40 upon the opening and closing of the door on the other side of the doorway.

The invention further comprises certain 45 subsidiary devices, valves, by-passes, levers, links, etc., whereby when the door is opened and closed upon one side of the doorway, one set of devices (spring and check) is operative for closing the door and retarding 50 and checking its swing, while the other set (spring and check) is rendered noninterferent, and vice versa.

The invention further comprises certain

provisions of leverage, whereby the door is held closed with maximum effect, yet may be 55 opened with diminishing effort.

The invention further comprises means for regulating the various door-closing and door-checking mechanisms, and especially for independently regulating any one or 60 more of the said four mechanisms.

The invention consists of each and all of the foregoing features and combinations, and of certain details of construction and arrangement hereinafter set forth and 65 claimed.

The invention will be best understood by referring to the annexed drawings which show a preferred embodiment thereof as applied to a double-acting door (though it 70 will be understood that the invention may be applied to a single-acting door).

In these drawings, Figure 1 is an elevation, broken away through the center, and partly in section at the bottom, showing a 75 double-acting door mounted in its bearings and in its normal closed position; this figure is on a smaller scale than the remaining views; Fig. 2 is a horizontal section through line *a—a* of Fig. 1, the door being in closed 80 position; Fig. 3 is a vertical section through line *b—b* of Fig. 2; Fig. 4 is a plan or top view of the casing shown in Fig. 1, the door and part of its hinge-plate being removed; Fig. 5 is a horizontal section on line *c—c* of 85 Fig. 3, being located below the section shown in Fig. 2, the parts having the position they occupy when the door is closed; Fig. 6 is a partial view similar to Fig. 5, the door being indicated in one of its two open positions; Fig. 7 is an enlarged detail of one of 90 the pistons, showing a ball valve; Fig. 8 is a view similar to Fig. 2, except the door is shown in one of its opened positions; Fig. 9 is a transverse vertical section through line 95 *d—d* of Fig. 2, as viewed from the right; Fig. 10 is a vertical section through line *e—e* of Fig. 4, showing one of the springs and adjacent parts for adjusting its tension; Fig. 11 is a detail elevation, of the main 100 shaft which constitutes one of the door-pivots; and Fig. 12 is a top view of the shaft shown in Fig. 11.

In Fig. 1, the door is shown as mounted on vertical shafts or pivots 2 and 3, to swing 105 open on either side of the doorway, being

indicated as in its closed or "normal" position. To the bottom edge of the door is secured the slotted plate 4, which latter engages the correspondingly-shaped upper end 5 of shaft 3 (Fig. 4), thus locking the door and shaft 3 together so that the turning of either on its axis carries the other with it. The operating-devices are inclosed in casing 5, which is located in the sill 6 beneath the 10 door and provided with a cover 7 that lies flush with the sill. These operating-devices are connected to shaft 3, which thus becomes the operating-shaft, transmitting movement from the door to the mechanism and vice 15 versa. This shaft 3 is located near one end of casing 5, its lower end turning on the ball-bearing 10 (Fig. 3), while its upper bearing is in the collar 8 which is threaded into the top wall of the casing. In the present instance the operating-shaft 3 extends upward from casing 5 which is located beneath the door; but the casing might be inverted and located in the upper lintel, above the door.

25 Within the casing and adjacent the shaft 3 are the two horizontally-extending cylinders 34 and 35, of the liquid checking mechanism or check, with their pistons 36 and 37; and beyond them the vertically-arranged 30 helical spring 11 and the oppositely-wound helical spring 12 (Figs. 5 and 2).

The four parts are suitably connected to the operating-shaft 3 so that one spring and one check are called into play and co-act 35 positively and without fail upon the opening and closing of the door at one side of the doorway, without interference from the other spring and check; and, vice versa, they do not interfere when the door is opening 40 and closing upon the other side of the doorway, the other spring and check co-acting effectively during that period. The two checking-devices are similar in construction and mode of operation, and so are the two 45 springs.

Referring first to the springs, a vertical shaft 22 (Figs. 3 and 10) is located axially of each spring-coil, with its lower end journaling in a seat in the floor of casing 5, 50 while its upper end is transversely slotted to engage detachably the transverse pin 24 at the bottom of plate 25. This plate 25 is seated in an opening in cover 7 and lies flush therewith, and is provided with segmental seats 26 for locking it in various 55 positions of adjustment by means of screws 27 that take into cover 7 (Fig. 4), whereby shaft 22 is held against rotation. Upon the lower end of each shaft is keyed, by pin 33, 60 the disk or fixed anchor 32, to which the lower end of the spring is made fast. Upon this same shaft 22 is mounted a freely-turning sleeve carrying at its upper end the disk or movable anchor 14, to which is secured 65 the upper end of the spring. From each

one of these upper anchor plates 14 there extends to the operating shaft 3 an independent connection, comprising preferably a plurality of links whose remotest member (13 and 19 respectively) is comparatively short and is pivoted to crank-ears 17-17 upon shaft 3. Axial turning of shaft 3 in one direction winds up one spring, and turning of the shaft in the other direction winds up the other spring. Depending from the 75 cover 7 is a lug or stop 14² adjacent the rear of the first link 15 of one spring (Figs. 2 and 3); while a similar stop 14³ is provided for the first link 20 of the other spring.

Preferably the sides and rear of shaft 3, 80 at the level of short links 13-19 (as seen in Figs. 2, 8 and 11), provide a cam-surface that affords maximum leverage for the tension or pull of each of the two springs when the door is closed (Fig. 2), while the 85 stops 14² and 14³ limit the extent of pull of each spring; whereas, in the opened position of the door (Fig. 8,) the minimum leverage is afforded the tension or pull of the then-operating (left-hand) spring 11, while 90 the collapsing or folding of the links 19 and 21 and the presence of stop 14³ render the other (right-hand) spring 12 inactive. But such cam-surface of the shaft 3 may be dispensed with, and the outer links (13 and 19) 95 connected to shaft 3 at one side of the dead center, in which case the ordinary effect of the rotation of shaft 3, in moving the pivot of link 13 (or 19) through the quadrant, may be relied on for lessening the leverage 100 of the springs.

In the normal closed position each spring tends to draw its links toward it (to the right in Fig. 2), while the shoulders 14² and 14³ prevent either spring from preponderating 105 over the other and forcing the door past its normal closed position. In practice, particularly in case of entrance doors for tall buildings, the spring that resists the opening of the door inward (as by gusts of 110 wind) will preferably have the greater tension or pull,—that is, will be much "stiffer" than the other spring; and the function of the stops is to prevent the stiffer spring forcing the door outward beyond the normal 115 closed position.

When a person undertakes to push against the door to open it, at the outset he has to overcome the greater leverage and maximum resistance offered by the proper spring; but 120 as the door is swung wider and wider open, the leverage of the spring diminishes. In like manner, as the door closes (and for the present disregarding the checking-devices) the leverage of the spring increases, so that 125 its maximum efficiency becomes available in holding the door closed. To adjust the tension of either spring, the screws 27 (that lock its plate 25) are loosened, and a spanner wrench 31 (Figs. 4 and 10) is applied 130

to the holes 29 in plate 25 to turn the latter, and with it the shaft 22 and the lower anchorage 32 of the spring. When the proper tension is obtained, screws 27 are replaced, engaging the adjacent segments 26, and holding shaft 22 and the fixed spring-anchor 32 stationary.

The preferable construction and arrangement of the checking-devices may be seen in Figs. 5 and 6, as consisting of two parallel and horizontally-disposed cylinders 34 and 35, with pistons 36 and 37, located near the operating-shaft 3, and between said shaft and the springs 11 and 12. The cylinders 15 are open at their forward end adjacent the shaft 3, and closed at the other or rear end. A connecting-pitman 38, 39, is pivoted to each piston and to the shaft 3, so as to afford the preferable positive connection between 20 the door and the checking-device. When the door 1 is in its normal closed position, the two pistons lie side by side, midway of the cylinders, and the pivot-connection of each piston to shaft 3 is at one side of the 25 "dead center"; and the parts are so arranged that when one piston moves inward the other moves outward; and vice versa. Located in the wall of cylinder 34 is a longitudinal by-pass 40, whose forward end opens 30 just in front of said normal median position of piston 36, while the rear end of the by-pass opens into the cylinder at the extreme rear of the latter; and similarly located in the wall of the other cylinder 35 is a similar 35 by-pass 41. Transversely through the wall of cylinder 34, in the rear portion thereof, extends a small port or vent 42 (Fig. 2), preferably located in the upper portion of said wall, and a similar vent 44 is similarly located 40 in the other cylinder 35; and the restricted passage through these comparatively-minute vents is regulated by the adjacent manually-adjusted screw-plugs 43, in cover 7, whose tips can enter vents 42 and 44 more or less 45 (Fig. 3). Through each piston-head extends a valve-port, in which is seated a ball-valve 45 held against escape by a transverse pin 46 (Fig. 7), thus affording an automatic valve that permits free passage from the front to the rear of the piston (from left to right) while automatically preventing passage therethrough in the opposite direction. The entire casing 5 is filled with the usual (heavy) oil employed in liquid 50 checking-devices, which enters the cylinders and will pass freely through the various by-passes and ports when permitted.

Fig. 5 is the normal position of rest, the door being closed. When the door 1 is opened, as in a direction away from the observer (or toward the top of the sheet in Fig. 6), the adjacent piston 36 moves forward from its normal median position and approaches shaft 3, the oil flowing freely 55 past its ball-valve 45 so that this piston 36 is

not now retarding or checking the swing of the door in opening, although its by-pass 40 becomes shut off by the piston, while the other piston 37 moves rearward, away from shaft 3, the oil passing freely around it 70 through its by-pass 41 so that this other piston 37 also is not at this stage checking the swing of the door. When the door 1 is released and spring 11 is closing it, the last-named piston 37 returns to its normal median position, oil flowing freely past its ball-valve 45 and through its by-pass 41; while the piston 36 checks and retards the closing-movement, since no oil can flow past its ball-valve 45 or through the by-pass 40 (which during this operation is closed by the piston),—the only escape for the oil beneath piston 36 being through the restricted vent 42. And the door, because of its positive connection to the piston, cannot close in advance of the slowly-traveling piston. In like manner, should the door be opened in a direction toward the observer (as toward the bottom of the sheet in Figs. 5 and 6), the then-adjacent piston 37 moves forward from 80 its median position (Fig. 5), while the other piston moves rearward, neither piston checking the swing of the door; and when the door swings back, the adjacent piston 37 retards and checks the movement while the other 85 piston 36 is not checking. The operative checking-travel of each piston is from the extreme left of its cylinder to its median position; its travel from midway of the cylinder to the extreme left thereof merely 90 places it where it is ready to operate; while its movements, in either direction, in the right-hand half of the cylinder are merely 95 idle reciprocations (so far as checking is concerned), and neither piston there opposes the opening of the door in either direction. In short, when the door is opening and closing upon one side of the doorway, one set 100 or combination of devices (one spring and one check and their connections) cooperates in closing and checking the door, while the other set co-operates to the extent of being rendered idle,—that is to say, of not interfering with the first-named set; and vice versa. Moreover, as already explained each 115 one of the two spring-devices and each one of the two checking-devices can be independently regulated for varying conditions.

The location of the connection of each pitman upon shaft 3 is such as to decrease 120 the leverage exerted upon the piston by the door as it approaches its normal closed position; that is, the initial opposition of the check is comparatively slight, but at the end becomes considerable,—thereby being correlated to the increasing tension or pull of its co-operating spring 11 or 12. In other words, in closing the door, as the tension or pull of the spring increases, the effective opposition of the check likewise increases. 130

The checking-action of each check may be independently regulated by turning its screw 43 in or out to regulate the size of the restricted passageway through the vents 5 42 or 44 respectively.

Although I have described with considerable detail the construction and arrangement of the devices entering into my invention, and their relative locations and connections, my invention is not limited in those respects, which are specifically disclosed merely for the sake of clearness.

Changes may be made in the construction and arrangement and location of the various devices, modifications may be resorted to, and parts may be used to the exclusion of other parts, without departing from the spirit of my invention, which is set forth in the annexed claims.

20. I claim—

1. In a door-closer and check, the combination with closing-mechanism carried independently of the door and including a shaft adapted to be secured rigidly to the door to 25 constitute one hinge-pintle therefor so as to be turned upon movement of the door between the open and closed positions and spring-mechanism upon one side of the shaft opposing the movement of said shaft when 30 the door is being opened, of checking-mechanism carried independently of the door and being distinct from the spring-mechanism, which checking-mechanism is so located that its line of action passes to one 35 side of the axis of the shaft when the door is in a closed position.

2. In a door-closer and check, the combination with closing-mechanism carried independently of the door, including a shaft 40 for operative connection with the door and adapted to be turned upon movement of the door between its open and closed positions, and spring-mechanism upon one side of the shaft and having positive connection with 45 said shaft and opposing the movement thereof when the door is being opened, of checking-mechanism distinct from said spring-mechanism and comprising a cylinder and a piston, and positive connection between 50 said piston and said shaft.

3. In a door-closer and check, the combination with closing-mechanism carried independently of the door, including a shaft for operative connection with the door and 55 adapted to be turned upon movement of the door between its open and closed positions, and spring-mechanism upon one side of said shaft and having positive connection to said shaft and opposing the movement thereof 60 when the door is being opened, of liquid checking-mechanism distinct from said spring-mechanism and comprising a piston and a cylinder and valving-means for permitting liquid to pass from one side of said 65 piston to the other.

4. The herein-described self-contained door-closer and check, comprising the combination with a closed casing, of a shaft journaled therein and adapted to be turned upon movement of the door between its open and closed positions, spring-mechanism inclosed in the same compartment of said casing upon one side of said shaft and opposing the movement thereof when the door is being opened, liquid checking-mechanism located 70 within the same casing and distinct from said spring-mechanism, said checking-mechanism comprising a cylinder and piston and positive connection between said shaft and said piston.

5. The herein-described self-contained door-closer and check, comprising the combination with a closed casing, of a shaft journaled therein and adapted to be turned upon movement of the door between its open and closed positions, spring-mechanism inclosed in said casing upon one side of said shaft and opposing the movement thereof when the door is being opened, liquid checking-mechanism located within the same compartment of said casing and distinct from said spring-mechanism, said checking-mechanism comprising a cylinder and a piston with a valve for permitting liquid to pass from one side of the piston to the other, and 90 positive connection between said shaft and said piston.

6. A door-closer and check for double-acting doors, comprising the combination of a shaft for operative connection with the door and adapted to be rotated by the swing of the door between its open and closed positions, spring-mechanism acting upon said shaft to oppose the opening of the door in either direction and serving to close the door 100 when released, a checking-device to oppose the closing-movement of the door from one direction, and a second checking-device to oppose the reverse closing-movement of the door, said checking-device being so arranged 105 and connected that the line of action of each is located to one side of the dead center of said shaft when the door is in closed position.

7. A door-closer and check for double-acting doors, comprising the combination of a 115 shaft for operative connection with the door and adapted to be rotated by the swing of the door between its open and closed positions, spring-mechanism acting upon said shaft to oppose the opening of the door in 120 either direction and serving to close the door when released, a checking-device comprising a piston pivotally connected to said shaft and opposing the closing movement of the door from one direction, and a second checking-device comprising a piston pivotally connected to said shaft and opposing the reverse closing-movement of said door, said checking-device being so arranged and connected that the line of action of each is lo- 125 130

cated to one side of the dead center of said shaft when the door is in closed position.

8. In a door-closer and check mounted independently of the door, the combination of a shaft adapted to be operatively connected to the door so as to be oscillated by the swinging of the door, spring-mechanism, a connection between the same and said shaft whereby the spring opposes the opening of the door, checking-mechanism including a cylinder and a piston mounted independently of said spring, and a pivotal connection between said piston and said shaft that is independent of the connection for said spring-mechanism, said connection for the checking-mechanism being located at one side of the dead center when the door is closed.

9. In a door-closer and check, the combination of a shaft adapted for operative connection with the door so as to be oscillated by the swinging of the door, mechanism to oppose the opening of the door, and liquid checking-mechanism to retard the closing of the door, said checking-mechanism comprising a piston and cylinder, and having a passage with an automatic valve that prevents the flow of liquid therethrough while the piston is retarding the closing-movement of the door, having also a second passage that is closed by said piston during all the period while thus retarding, and having means to permit restricted flow of liquid therethrough.

10. In a door-closer and check for double-acting doors, the combination of a shaft adapted to be operatively connected to the door so as to be oscillated upon swing of the door in either direction, spring-mechanism connected to said shaft for closing said door from either direction, a liquid checking-device comprising a cylinder and a piston connected positively to said shaft and that opposes the closing of said door from one direction, a similar positively connected checking-device opposing such movement from the opposite direction, and means comprising an automatic valve and a by-pass whereby liquid is permitted to flow freely through both of said checking-devices when the door is being opened but when the door is closing is permitted to flow freely through only one of said devices and is retarded from flowing through the other.

11. In a door-closer and check for double-acting doors, the combination of a shaft adapted to be operatively connected to the door so as to be oscillated upon swing of the door in either direction, mechanism for closing said door, two liquid checking-devices comprising each a cylinder and piston that opposes the closing movement of said door each in its own direction, each checking-device containing a by-pass adapted to be sealed by its piston during all the period while the latter is retarding the door-closing movement, and containing also a valve that

closes automatically against the passage of liquid while the piston is thus retarding.

12. In a door-closer and check, the combination with closing-mechanism carried independently of the door and including a shaft adapted for rigid connection to the door and which is adapted to be turned with the door upon movement of the door between the open and closed positions, and spring-mechanism opposing the movement of said shaft when the door is being opened, of liquid checking-mechanism carried independently of the door and being distinct from the spring-mechanism, said checking-mechanism comprising a piston pivotally secured to said shaft and having its line of action lying to one side of the dead-center when the door is closed.

13. In a door closer and check for double-acting doors, the combination of a shaft adapted to be secured rigidly to a door to constitute one hinge-pintle therefor, a spring operatively connected to said shaft and serving to close the door from its open position at one side of the doorway, a second spring similarly connected to close the door from its open position at the other side of the doorway, liquid checking-mechanism including a piston connected to said shaft and opposing the closing of the door from either direction, and means including an automatic check-valve connected with said checking-mechanism to prevent said checking-mechanism from opposing the opening of the door in either direction.

14. A door-closing and checking device for double-acting doors, comprising the combination of a shaft adapted to be secured rigidly to the door to constitute one hinge-pintle therefor, spring-mechanism operatively connected to said shaft to oppose the opening of the door in either direction, checking-mechanism comprising a piston pivotally connected to said shaft to oppose the closing of the door from one direction, separate checking-mechanism comprising a piston pivotally connected to oppose the closing from the other direction, and means including an automatic check-valve to prevent said checking-mechanisms from opposing the opening of the door.

15. An interchangeable door-closer and check, comprising the combination of a casing containing a vertical shaft journaled therein and adapted to be turned by the swing of the door and to control the latter, spring-mechanism located within said casing the operative relation thereof to said shaft being such that said spring is attaining its maximum efficiency as the door is approaching its closed position, and liquid checking-mechanism also located in said casing and having a piston pivotally connected to said shaft to oppose the closing of the door and said checking-mechanism being so arranged

and connected as to be attaining its maximum opposition as the door approximates its closed position.

16. A door-closing and checking device for double-acting doors, comprising the combination of a shaft adapted to be operatively connected to the door, mechanism positively and operatively connected to said shaft to oppose the opening of the door in one direction and tending to close it from that direction, independent mechanism positively and operatively connected to said shaft and tending to oppose the opening of the door in its opposite direction and tending to close it from that last-named direction, checking-mechanism comprising a piston pivotally connected to said shaft to oppose the closing of the door in either direction, and means including an automatic check-valve connected with said checking-mechanism to prevent the latter from opposing the opening of the door.

17. A door-closing and checking device for double-acting doors, comprising the combination of a shaft adapted to be operatively connected to the door, spring-mechanism connected to said shaft to oppose the opening of the door in one direction and tending to close it from that direction, independent spring-mechanism connected to said shaft and tending to oppose the opening of the door in its opposite direction and tending to close it from the last-named direction, flexible connections between said shaft and each of said mechanisms whereby each mechanism will operate only when the door is opened or closed in the direction pertaining to that mechanism, liquid checking-mechanism comprising a piston pivotally connected to said shaft to oppose the closing of the door in either direction, and means including an automatic check-valve connected with said checking-mechanism to prevent the latter from opposing the opening of the door.

18. The combination with a double-acting door, of checking-mechanism therefor comprising two checking-devices, one opposing the closing of the door from one direction only, and the other opposing the closing of the door from the other direction only, and means comprising liquid-passages and valving-devices therefor for preventing both of said devices from opposing the opening of the door from either direction.

19. The combination with a double-acting door, of a shaft connected operatively to the door, checking-mechanism comprising pistons for respectively opposing the closing of the door from either direction, a connection pivotally secured to each piston and to said shaft and lying to one side of the dead center when the door is in the closed position.

65 20. A liquid checking-mechanism for

double-acting doors, comprising a cylinder and piston adapted for operative relation to the door, a by-pass, valve-means actuated by the swing of the door for sealing said by-pass during all the period while the piston is serving to check the door-movement, an automatic valve for preventing flow of liquid past the piston when the latter is serving to check said closing-movement but permitting such flow when the said piston is not checking, and means for permitting restricted flow of the liquid due to pressure of the piston thereupon when said piston is checking the closing-movement of the door.

70 21. In a door-closer and check for double-acting doors, the combination of a door-closing device and a door-checking device co-acting when the door is opening and closing upon one side of its doorway, a second door-closing device and a second door-checking device co-acting when the door is opening and closing on the other side of the doorway, and means for independently adjusting each of said four devices.

80 22. In a door-closer and check for double-acting doors, the combination of a door-closing device and a door-checking device co-acting when the door is opening and closing upon one side of its doorway, a second door-closing device and a second door-checking device co-acting when the door is opening and closing on the other side of the doorway, and means including flexible connections for said closing-devices and liquid bypasses for said checking-devices whereby when either pair of closing and checking devices is acting upon the door the other pair is rendered non-interfering therewith.

90 23. In a door-closer and check for double-acting doors, the combination of a door-closing device and a door-checking device co-acting when the door is opening and closing upon one side of its doorway, a second door-closing device and a second door-checking device co-acting when the door is opening and closing on the other side of the doorway, and lever-connections whereby each door-closing device increases its pull as the door is closing and exerts its maximum pull when the door is closed.

105 24. In a door-closer and check for double-acting doors, the combination of a door-closing device and a door-checking device co-acting when the door is opening and closing upon one side of its doorway, a second door-closing device and the second door-checking device co-acting when the door is opening and closing on the other side of the doorway, and lever-connections whereby each checking-device exerts its minimum opposition when the door begins to close and gradually increases to its maximum opposition at the moment of closing the door.

115 25. A liquid checking-mechanism for double-acting doors, comprising a cylinder

and piston adapted for operative relation to the door, a by-pass, valve-means actuated by the swing of the door for sealing said by-pass during all the period while the piston is serving to check the door-closing, and an automatic valve for preventing flow of liquid past the piston when the latter is serving to check said closing-movement.

26. The combination, with a double-acting door, of a shaft connected operatively to the door, checking-mechanism comprising a cylinder and piston, the piston occupying a neutral position in said cylinder when the door is in a closed position, operative connection between said shaft and said piston whereby the piston is movable in either direction from its neutral position in said cylinder.

27. A liquid checking - mechanism for double-acting doors, comprising a cylinder and piston adapted for operative relation to the door, valve-means for permitting liquid to pass freely from one side of the piston to the other side of the piston when the door opens in one direction, and valve-means for permitting liquid to pass freely from the last-named side of the piston to the first-named side of the piston when the door opens in the other direction.

28. A liquid checking - mechanism for double-acting doors, comprising two cylinders each having a piston adapted for operative relation to the door, valve-means for permitting liquid to pass freely from one side of each piston to the other side thereof when the door opens in one direction, valve-means for permitting liquid to pass freely from the last-named side of each piston to

the first-named side thereof when the door opens in the other direction, and valve-means for restricting flow of liquid on the closing of the door from each direction.

29. The combination, with a double-acting door, of a shaft connected operatively to said door, checking-mechanism comprising a cylinder and a piston, operative relation between said shaft and said piston whereby by the swing of the door in either direction said piston is movable from the position it occupies when the door is in its closed position.

30. In a door-closer and check mounted independently of the door, the combination of a shaft adapted to be operatively connected to the door so as to be oscillated by the swinging of the door, spring-mechanism, a connection between the same and said shaft whereby the spring opposes the opening of the door, and checking-mechanism opposing the closing of the door, said checking-mechanism comprising a cylinder and a piston mounted independently of said spring, and said piston having operative connection with said shaft that is independent of the connection for said spring-mechanism, said connection for the checking-mechanism being located to one side of the dead center when the door is closed.

In witness wherof, I hereunto subscribe my name this second day of February A. D., 1909.

OSCAR C. RIXSON.

Witnesses:

J. R. LAWS,
GEORGE PRINGLE.

and piston adapted for operative relation to the door, a by-pass, valve-means actuated by the swing of the door for sealing said by-pass during all the period while the piston is serving to check the door-closing, and an automatic valve for preventing flow of liquid past the piston when the latter is serving to check said closing-movement.

26. The combination, with a double-acting door, of a shaft connected operatively to the door, checking-mechanism comprising a cylinder and piston, the piston occupying a neutral position in said cylinder when the door is in a closed position, operative connection 10 between said shaft and said piston whereby the piston is movable in either direction from its neutral position in said cylinder.

27. A liquid checking-mechanism for double-acting doors, comprising a cylinder 20 and piston adapted for operative relation to the door, valve-means for permitting liquid to pass freely from one side of the piston to the other side of the piston when the door opens in one direction, and valve- 25 means for permitting liquid to pass freely from the last-named side of the piston to the first-named side of the piston when the door opens in the other direction.

28. A liquid checking-mechanism for double-acting doors, comprising two cylinders each having a piston adapted for operative relation to the door, valve-means for permitting liquid to pass freely from one side of each piston to the other side thereof 35 when the door opens in one direction, valve- means for permitting liquid to pass freely from the last-named side of each piston to

the first-named side thereof when the door opens in the other direction, and valve-means for restricting flow of liquid on the 40 closing of the door from each direction.

29. The combination, with a double-acting door, of a shaft connected operatively to said door, checking-mechanism comprising a cylinder and a piston, operative relation between said shaft and said piston whereby by the swing of the door in either direction said piston is movable from the position it occupies when the door is in its closed position. 45

30. In a door-closer and check mounted independently of the door, the combination of a shaft adapted to be operatively connected to the door so as to be oscillated by the swinging of the door, spring-mechanism, a 50 connection between the same and said shaft whereby the spring opposes the opening of the door, and checking-mechanism opposing the closing of the door, said checking-mechanism comprising a cylinder and a piston 55 mounted independently of said spring, and said piston having operative connection with said shaft that is independent of the connection for said spring-mechanism, said connection for the checking-mechanism being located to one side of the dead center when the door is closed.

In witness whereof, I hereunto subscribe my name this second day of February A. D., 1909.
